(57) **CLAIM**

I claim the ornamental design for a robotic creature, as shown and described.

DESCRIPTION

FIG. 1 is an isometric view, from the top front left, of the robotic creature.

FIG. 2 is an isometric view, from the bottom back right, of the robotic creature.

FIG. 3 is a plan view from the top of the robotic creature.

FIG. 4 is an elevation view from the front of the robotic creature.

FIG. 5 is an elevation view from the left side of the robotic creature.

FIG. 6 is an elevation view from the back of the robotic creature.

FIG. 7 is an elevation view from the right side of the robotic creature.

FIG. 8 is a plan view from the bottom of the robotic creature.

FIG. 9 is an isometric view, from the top back right, of the robotic creature; and,

FIG. 10 is a cross sectional view of the robotic creature. The broken lines show portions of a robotic creature that form no part of the claimed design.

1 Claim, 4 Drawing Sheets
